AIR CONDITIONING SYSTEM FOR SUB-DIVIDED INHABITABLE ENCLOSURES

Richard W. Kritzer, Chicago, Ill., assignor to Peerless of America, Incorporated, a corporation of Illinois

Filed Jan. 8, 1962, Ser. No. 164,843

1 Claim. (Cl. 165—22)

The improved air conditioning system comprising the present invention has been designed for use primarily in connection with a modern multi-story apartment building, a single or multi-story motel, a house or other building which is subdivided into individual inhabitable quarters or enclosures, the present day architectural trend in designing such a building being well adapted to accommodate the principles of the present invention. The invention is, however, capable of other uses and an air conditioning system embodying such principles may, with or without modification, be employed for cooling, dehumidifying and heating an office building, a factory building, a large residential building or any other subdivided inhabitable enclosure where the comfort of human life is to be considered whether the building be of the multi-story type or whether all of the enclosures thereof be at a single level. Irrespective, however, of the particular use to which the invention may be put, the essential features thereof are at all times preserved.

Where large inhabitable buildings are concerned, and where such buildings are supplied with both heating and cooling facilities for the individual subdivisions or apartments thereof, two types of air conditioning systems are now commonly in use. While the individual installations may vary widely in the details thereof, the system, nevertheless, may be broadly classified as either a four-pipe system or a three-pipe system, depending upon the number of feed and return pipes which are used for feeding the heating and cooling media generally to and returning the same from the individual apartments which are to be heated or cooled at will.

In the four-pipe system, a hot water feed pipe and a hot water return pipe carry the water in a closed path through whatever heat exchange device may be installed in the individual apartments and the use of such hot water is under the selective control of the individual tenant who, by opening or closing a valve or valves, may cause the hot water to be circulated through the heat exchange units of his individual localized heating installation. The hot water employed for this tenant-controlled heating is furnished by the management and generally emanates from a water heater or boiler which usually is installed in the basement of the building. Chilled water is similarly furnished by the management and this water generally emanates from a cooler which is also usually located in the basement of the building. The chilled water is pumped to the heat exchange units in the individual apartments through feed and return pipes which are entirely separate from the riser and return pipes for the hot water and thus, collectively, four such feed and return pipes are embodied in such a system. The heat exchange devices or units in the individual apartments which serve for heating the air to be circulated through the apartments in some instances are the same heat exchange devices which serve for cooling such air. In other installations, separate heat exchange devices are employed for heating and cooling respectively. In either event, four manifold or feed and return pipes are employed in the system and, invariably, the feed pipes for hot and cold water respectively, and sometimes the return pipes, are heavily insulated or jacketed to prevent heat losses. In a four-pipe system of this character, the tenant, by turning suitable valves, may establish or discontinue the heating or cooling effect, but his control is usually subject to the seasonal control by

2

the management which supplies hot or cold water according to its own dictates as determined by the weather.

In a three-pipe system, the basement installation, including the boiler and water cooler, remains the same as in the four-pipe system. A hot water feed pipe and a cold water feed pipe furnish hot and cold water, respectively, to the various heat exchange devices in the individual apartments, but a common return pipe is employed for both hot and cold water. Again, it is found necessary heavily to insulate or jacket the feed pipes. Likewise, as in the case of a four-pipe system, the limited tenant control whereby the tenant may initiate or discontinue heating or cooling effects, is subject to management control on a seasonal basis. In the three-pipe system, quick change-over operations from heating to cooling and vice versa are not possible inasmuch as it frequently requires many hours for the system to rid itself of heat when cooling is to be initiated, or to assimilate heat after a period of cooling. Furthermore, the individual tenant is not always aware of any act taken by the management with respect to the system as a whole and, unless notified by the management, he may not be apprised of the fact that either cooling or heating facilities are available to him.

Both the four-pipe system and the three-pipe system briefly outlined above are possessed of numerous disadvantages, principal among which is the high cost of the initial installation, as well as the cost of maintenance. Additionally, in any temperate zone climate, there are off-seasonal periods when certain tenants may have a demand for heating while other tenants may, at the same time, have a requirement for cooling. It frequently happens that the tenants who are located on the east side of an apartment building will have a demand for cool air during morning hours when the sun is on their side of the building, while at the same time, the tenants on the west side of the building will have a demand for hot air. Conversely, during the afternoon hours, the tenants on the east side of the building may feel the need for heat while the tenants on the west side of the building may require or desire cooling. In the four-pipe system, the necessary selective controls for both heating and cooling may be made available to the tenant by the management but only at the comparatively great cost of maintaining both the heating plant and the cooling plant in simultaneous operation. In actual practice, few managements will go to such expense. In the three-pipe system, such selective controls are not effective to the tenant even if the management were willing to maintain both the heating and the cooling system in simultaneous operation, such unavailability being due to the aforementioned length of time required for change-over operations, and also to the fact that the mixing of hot and cold water in the return pipe lowers the efficiency of the water circulating system in both the heating and the cooling plants.

The present invention is designed to overcome the above-noted limitations that are attendant upon the construction and use of both four and three-pipe systems of air conditioning and, toward this end, it contemplates the provision of a two-pipe system involving the use of only a feed pipe and a return pipe in series in a closed hydraulic circuit, the water furnished by the feed pipe being made available to the individual tenants on a seasonal basis for direct use for heating purposes, or for indirect use by the tenant for cooling purposes, the tenant thus being able, optionally, to use such water either for heating or for cooling, according to his individual preference. Thus, according to the present invention, although the same water at a given temperature is furnished to all of the apartments in common, certain tenants, feeling the need for heat, may use this water for heating purposes, while other tenants, feeling the need for cooling, may use the same water for cooling purposes.

Generally speaking, the improved two-pipe air conditioning system embodying the present invention comprises a feed pipe and a return pipe in series and the vicinity or proximity of the various building enclosures (apartments) to be air conditioned; means for flowing moderately warm water (85° to 90° F.) successively through the feed and return pipes; a heat exchange device disposed in each enclosure, connected to receive water from the feed pipe and to return the water to the return pipe, and adapted when rendered operative to heat the air in its associated enclosure; an air conditioning unit disposed in each enclosure, embodying a water-cooled condenser, having the condenser connected to receive water from the feed pipe and to return the water to the return pipe, and adapted when rendered operative to cool the air in its associated enclosure; and means associated with each enclosure for selectively rendering operative the heat exchange device or the air conditioning unit of the associated enclosure.

Briefly, in carrying out the invention, it is contemplated that the management shall have control over a supply of water and be able either to heat such water or to cool it to a desired or predetermined temperature on a seasonal basis. For this purpose, there may be provided a water heater or boiler and a water cooler or chiller, both instrumentalities being preferably located in the basement of the building in which the system is installed. Additional equipment under the control of the management includes a pump and suitable valve means whereby either the boiler or the cooler, each to the exclusion of the other, may be placed in series in a closed hydraulic circuit including the feed and return pipes which are common to all of the apartments. The valve means also is operable to exclude both the boiler and the cooler from the closed circuit flow of water through the feed and return pipes. Each tenant has under his own exclusive control two heat exchange units, one for heating purposes and the other for cooling purposes, and a fan or blower common to both units. The heater, which is employed for heating purposes, will hereinafter be referred to simply as the hot water heater, or simply the heater, is operatively connected to the feed pipe and to the return pipe. A shut-off valve in series with the heater, when open, allows the water to flow from the feed pipe through the heater and to be discharged to the return pipe. The heat exchange unit which is employed for cooling purposes will hereinafter be referred to as the water cooler or simply the cooler constitutes the evaporator unit of a complete so-called electrically powered air conditioner of conventional design and including a compressor, a water-cooled condenser, an expansion valve or its equivalent, and the above-mentioned evaporator unit or cooler. The compressor, condenser, expansion valve and evaporator or cooler are operatively connected together in series in a refrigerant circuit in the usual manner of connecting such instrumentalities, and the water phase of the water-cooled condenser is operatively connected to the feed and return pipes under control of suitable valve means.

With this equipment under his exclusive control, each tenant may open one valve and allow water at a seasonally predetermined temperature to flow through the heater for heating purposes or, alternatively, he may, by closing that valve and opening another valve, supply the same water to the water-cooled condenser of his air conditioning equipment for removing heat from the compressed refrigerant which flows to the condenser from the compressor so that after the thus cooled and compressed refrigerant has passed through the expansion valve and entered the evaporator, the desired cooling effect will be attained.

Many advantages accrue from such a two-pipe system, both from the standpoint of the management and of the various tenants. From the management's point of view, a distinct advantage resides in the fact that the major cost of cooling the air in any given apartment is almost entirely borne by each tenant who must pay for the electrical

current which is used in operating the air conditioner, i.e., in operating the electric motor which drives the refrigerant compressor and the current which is used in operating the fan which circulates the air through the cooler. It is the individual cooler in each apartment which, in the last analysis, performs the cooling function on the air undergoing circulation. The single water cooler or chiller under the control of the management need be used only to maintain the water in the closed circuit or pipe system below a predetermined maximum on the order of from 85° to 90° F., providing such water is not automatically maintained below such temperature by normal tenant use. Frequently, and for long periods of time, the system will maintain itself in a condition of "balance" wherein the management need neither heat or cool the water in the system inasmuch as such tenants as are using their equipment for cooling purposes will discharge hot water into the return pipe, such water having been heated by heat exchange phenomena incident to cooling of the hot compressed refrigerant in the condenser. Conversely, such tenants as are using their equipment for heating purposes will discharge relatively cool water into the return pipe. In instances such as have been briefly outlined above where the tenants on the opposite sides of the building have different air conditioning requirements, one group having a demand for heat and the other group having a demand for cooling, the discharge of relatively cold water and hot water, respectively, into the return pipe will establish a condition of balance where the water maintained in the closed circuit system remains within a predetermined range so that the management need resort to neither heating nor cooling of the water in the system. A further advantage that accrues to the management resides in the fact that the manual attention and control which are required to be exerted over any given period of time are at a minimum. The system makes provision for automatic thermostatic control of the temperature of the water in the system during in-between season weather where the water is to be maintained within a predetermined temperature range where it is available to the tenants on a selective basis for either heating or cooling purposes as determined by the individual tenants. If the water in the return pipe runs too hot so that the necessary temperature differential for effective and economical cooling of the condenser tubes cannot be maintained, provision is made for cutting in the master water cooler to bring the temperature of such water down to the predetermined range. Conversely, if the water in the return pipe runs too cold for use by the tenants in their respective heaters, provision is made for cutting in the water heater or boiler to bring the temperature of such water up to the predetermined range. This leaves only well defined seasonal temperature differentials for the management to reckon with. A final advantage of the present heating system to the management resides in the fact that only two manifold pipes are required and neither of these need be insulated or jacketed because the water flowing through the closed circuit or pipe system is always above the dew point.

From the tenant's point of view, the system has the advantage that, during middle temperature periods, it is elective with him whether the air in his quarters be heated or cooled and this election on his part is available to him twenty-four hours during each day when there is a possibility that he may require one or the other type of air conditioning. The election is made unavailable to him only during extremely cold weather, i.e., midwinter temperatures when the management normally is supplying hot water for heating purposes and it is reasonably certain that no tenant will have a demand for cooling effects.

A further advantage of the present system accruing to both the management and the tenant arises from the fact that at no time when the system is in operation and during normal use thereof will the temperature of water in the system fall below the dew point, either in the feed

pipe or the return pipe or in the lead-in or branch pipes leading to the individual apartments. For this reason not only is there no need for pipe insulation at any point in the system, but no drainage system for moisture condensation is required.

The provision of an air conditioning system such as has briefly been outlined above and possessing the stated advantages being among the principal objects of the invention, numerous other objects and advantages will become readily apparent as the following description ensues.

In the accompanying three sheets of drawings forming a part of this specification one illustrative embodiment of the invention has been shown.

In these drawings:

FIG. 1 is a fragmentary vertical sectional view taken through a typical inhabitable enclosure of the apartment building type and showing, somewhat schematically, the improved air cooling and heating system operatively installed therein;

FIG. 2 is a fragmentary plan view, also schematic in its representation, of certain tenant-controlled equipment employed in connection with the present invention;

FIG. 3 is an enlarged sectional view taken substantially centrally through a control valve employed in connection with the present invention and showing the same in the condition it assumes when the system is being operated on a seasonal basis for apartment heating purposes only;

FIG. 4 is a sectional view similar to FIG. 3 but showing the control valve in the condition it assumes when the system is being operated on a seasonal basis for apartment cooling purposes only;

FIG. 5 is a sectional view similar to FIGS. 3 and 4 but showing the control valve in the condition it assumes during in-between season operation;

FIG. 6 is a circuit diagram showing the electrical circuit for a solenoid-actuated control valve employed in connection with the present invention; and

FIG. 7 is a circuit diagram showing the electrical circuit for one of a series of control thermostats employed in connection with the invention.

Brief description

Referring now to the drawings in detail, and in particular to FIG. 1, a preferred form of the present invention has been somewhat schematically shown as being applied to the air conditioning of a typical multi-story apartment building, the building being fragmentarily shown and designated in its entirety by the reference numeral 10. As heretofore indicated, the present air conditioning system is capable of being used in a single-story building. As shown in FIG. 1, only the central portion of the building 10 in the vicinity of the ground floor and second floor levels of the building has been illustrated, but it will be understood that the building may extend upward to any desired floor level. Two opposed inside building walls 12 and 14 form a part of a generally rectangular ventilating shaft 16, such a shaft being conventional and usually being disposed in the masonry of the building. The shaft 16 may constitute one of several such shafts associated with the building 10. The shaft 16 may, if desired, communicate with the atmosphere above the building roof so that the shaft may constitute a passageway for air to assist in ventilating the various apartments in associated relation with the shaft but, if desired, the upper end of the shaft may be closed to the atmosphere. In either event, the shaft 16 extends at least to a point above the level of the uppermost apartment floor and preferably to a point adjacent to the uppermost apartment ceiling. A feed pipe 18 for water extends upwardly through the ventilating shaft 16 and has its upper end connected through a reduction orifice device R to the upper end of a return pipe 20 which also extends through the ventilating shaft 16. The feed and return pipes constitute portions of a closed circuit water supply or pipe system as will be described presently.

In the illustrated portion of the building, the ground floor 19 constitutes the ceiling for the basement enclosure 22. A second floor 24 constitutes a ceiling for two apartment enclosures 26 and 28. A third floor 30 constitutes a ceiling for two additional apartment enclosures 32 and 34. The building may have additional floors and apartment enclosures above the previously-mentioned floors and apartment enclosures. The layout or plan of the various floors 19, 24 and 30 may be substantially identical and it may follow any acceptable apartment building layout, the various apartment subdivisions or walls which divide the apartments into kitchens, living rooms, bedrooms, bathrooms, etc. remaining undisclosed herein since the details thereof do not affect the air conditioning system of the present invention. The present air conditioning system is available, in the form illustrated herein, or in modified forms, for use in connection with a wide variety of apartment layouts or subdivisions.

The air conditioning system of the present invention includes two sets of instrumentalities, namely, instrumentalities which are common to all of the apartments, are operable under the control of the apartment building management, and are operated by and are the responsibility of the janitor, building engineer, superintendent or other similar personnel, and instrumentalities which are individual to each apartment and are operable under the control of the individual tenant. The instrumentalities which are operable under the control of the management of the apartment building are preferably located in the basement enclosure 22 or at least in a separate building enclosure provided for these instrumentalities. Such instrumentalities include means for selectively heating and cooling the water which is supplied to the closed circuit water system or, specifically, to the feed pipe 18. The instrumentalities which are operable under the control of the tenant are located in the individual apartment enclosures 26, 28, 32, 34.

Management controlled instrumentalities

40 The instrumentalities which are operable under the control of the apartment building management include a conventional hot water heater or boiler 40 which is installed on the basement floor 42 and has the usual lead-in and lead-out hot water pipes 44 and 46 associated therewith. The lead-out pipe 46 is connected to one of four ports of a four-way main control valve V. The valve V has another port connected through a pipe 48, a four-way fitting 50, and a pipe 52 to the outlet side 54 of a water pump 56 of conventional construction. A third port of the valve V is connected through a pipe 58 to a conventional water cooler or chiller 60, this latter pipe constituting the lead-out pipe for such cooler. The lead-in pipe 62 of the cooler 60 is connected to the four-way fitting 50. A fourth port of the valve V is connected directly to the lower end of the feed pipe 18 which extends upwards through the shaft 16 of the building 10. The return pipe 20 has its lower end connected to the inlet side 64 of the water pump 56. A main control thermostat 66, the nature and function of which will be made clear presently, is interposed in the return pipe 20 and serves as a control instrumentality for the valve V, the latter being of the solenoid-actuated type.

The tenant controlled instrumentalities

65 The instrumentalities which are operable under the control of the individual tenants occupying the apartment enclosures 26, 28, 32, 34 are identical and, therefore, a description of one set of such instrumentalities will suffice for them all. Each apartment enclosure, for example, 70 the enclosure 28, is provided with a sub-ceiling 70 which is of limited extent and is disposed below the level of the ceiling 20. This sub-ceiling 70, in combination with a pair of vertical side walls 72 and 74 (see FIG. 2) and an end wall 76, defines an elevated plenum chamber 78, one end of which is open as at 80 and communicates with

the interior of the ventilating shaft 16. The end wall 76 is provided with a louvered grille 82 establishing communication between the interior of the plenum chamber 78 and the apartment enclosure 28. A motor driven fan assembly which has been designated in its entirety by the reference numeral 84 is disposed immediately behind the grille 82 and serves, when energized, to draw air from the interior of the plenum chamber 78 and force the same into the apartment enclosure 28.

Disposed within each plenum chamber 78 is a heat exchange device 90 of the finned tubing type. This heat exchange device, in combination with the fan assembly 84, constitutes an air circulating heater and it will hereinafter be referred to as such. The heater 90 is operatively connected by a branch conduit 92 to the feed pipe 18, and by a branch conduit 94 to the return pipe 20. A shut-off valve V2 is interposed in the conduit 92 where it is accessible to the tenant occupying the apartment enclosure 28.

Also disposed within the plenum chamber 78 is a complete so-called air conditioning assembly or unit 96 which is of the compressor-condenser-evaporator type and is identified in the drawings by the rectilinear dotted line enclosure of FIG. 2. The unit 96 includes the usual compressor 100, condenser 102 and evaporator 104. These three devices or units of the air conditioning unit are operatively connected together in a closed refrigerant circuit including a line 106 which leads from the compressor 100 to the condenser 102, a line 108 which leads from the condenser 102 to the evaporator 104, and a return refrigerant line 110 which leads from the evaporator 104 back to the compressor 100. The usual expansion valve 112 is interposed in the line 108. The compressor 100 is adapted to be driven by means of a belt and pulley connection 114 from an electric motor 116. The condenser 102 is of the water-cooled type and cooling water for the tubes thereof is obtained from the feed pipe 18 through a branch conduit 118 and is returned to the return pipe 20 through a branch conduit 120. The evaporator 104 is of the finned tubing type, which is to say that it is comprised of a length of tube stock 121 to which there are attached at closely spaced regions a series of heat-radiating fins 123 which are formed from flat fin stock. In the illustrated form of evaporator, the tube stock 121 is of serpentine configuration in that it consists of straight parallel reach sections connected together at their adjacent ends by reverse bends, only the reverse bends being visible in FIG. 2. The heater 90 may be similarly formed of finned tubing. A manual shut-off valve V3 which is accessible to the tenant of the apartment enclosure 28 is interposed in the conduit 118. The air conditioning unit 96 is purely conventional and no claim is made herein to any novelty associated with the same other than its association with the overall air conditioning system of the present invention.

As a precautionary measure, a thermostat 122 is operatively disposed in the branch conduit 118 ahead of the valve V3 and operates to open the electric circuit for the motor 116 when the temperature of water in the riser pipe 18 is above a predetermined maximum so that the tenant will be unable to operate the air conditioning assembly 96 unless the temperature of the cooling water supplied to the condenser 102 is within a predetermined efficient cooling range.

The two heat exchange units, i.e., the evaporator 104 and the heater 90 are disposed in tandem relationship and in close proximity to each other so that the fan assembly 84 may operate to draw air successively through these units, the air being selectively heated or cooled, according to which of the units is in operation.

The main control valve

The four-way main control valve V which is operable under control of the management, either manually or automatically through the medium of the thermostat 66,

may be of any suitable type capable of selectively establishing communication between the pipes 18 and 48, between the pipes 18 and 44, or between the pipes 18 and 58. The valve V selected for illustration herein is of the solenoid-actuated type and it includes a valve casing 130 (see FIGS. 3, 4 and 5) of generally cylindrical configuration and within which there is disposed a rotatable valve body 132. The valve body 132 is formed with an offset passage 134 therethrough. The valve V is essentially a three-position valve and is provided with a control handle 136 which, when in the position labelled A and shown in FIG. 3, causes the feed pipe 18 to be connected through the passage 134 to the pipe 48 leading from the four-way fitting 50. At the same time, portions of the valve body 132 block the ports leading to the pipes 46 and 58 so that the feed pipe 18 is effectively connected to the output side 54 of the pump 56.

When the control handle 136 is in the position labelled B and shown in FIG. 4, the feed pipe 18 is connected through the passage 134 to the lead-out pipe 46 for the boiler 40 while portions of the valve body 132 block the ports leading to the pipes 48 and 58 so that the feed pipe is effectively connected to the lead-out pipe extending from the boiler 40.

When the control handle 136 is in the position labelled C and shown in FIG. 5, the feed pipe 18 is connected through the passage 134 to the lead-out pipe 58 for the cooler 60, while portions of the valve body 132 block the ports leading to the pipes 46 and 48. The feed pipe 18 is thus effectively connected to the cooler 60.

As shown in FIG. 6, the control valve V is operable under the control of a dual solenoid winding 140 having sections B' and C'. The valve body 132 is normally biased so that when neither section of the solenoid winding 140 is energized, the valve assumes the condition wherein it is illustrated in FIG. 3 with the control handle 136 in the position indicated at A. The closed circuit for water in the system will then be through the pump 56 and the feed and return pipes 18 and 20 to the exclusion of both the heater 40 and the cooler 60. When the winding section B' is energized, the valve body 132 will assume the position wherein it is shown in FIG. 4 with the control handle in the position indicated at B. The closed circuit for water in the system will then be through the pump 56, the cooler 60, and the feed and return pipes 18 and 20. When the winding section C' is energized, the valve body 132 will assume the position wherein it is shown in FIG. 5 with the control handle in the position indicated at C. The closed circuit for water in the system will then be through the pump 56, boiler 40, and the feed and return pipes 18 and 20.

The circuit diagram of FIG. 6

In FIG. 6, the control circuitry for operating the valve V in order selectively to operate the boiler 40 and the cooler 60 when the system is set for normal automatic operation has been disclosed. The thermostat 66 may be of any well-known type, either bulb or contact, and its function in the system is to shift the position of the valve body 132 of the valve from its normal position wherein the pipes 18 and 48 are in communication to a position wherein the pipes 18 and 46 are in communication at such time as the temperature of water in the return pipe 20 falls below the predetermined 85° to 90° F. range, and to shift the valve body to a position wherein the pipes 18 and 58 are in communication when the temperature of water in the return pipe rises above this predetermined range.

The thermostat 66 selected for illustration is of the multi-contact type employing a movable bi-metallic strip 150 which is operable at a predetermined low temperature to close the #1 contacts and open the #2 contacts of a contact group 152, and is operable at a predetermined higher temperature to open the #1 contacts and close the #2 contacts. Upon closure of the #1 contacts due to a

flexing of the bi-metallic strip 150, a circuit will exist from one side 11 of the power line, through lead 13, #1 contacts of the contact group 150, leads 15 and 17, section C' of the solenoid winding 140, and leads 12 and 23 back to the other side 25 of the line. Energization of the section C' of the winding 140 will cause operation of the valve V so as to establish communication between the pipes 18 and 48, thus establishing a closed hydraulic circuit through the boiler 40 in a manner presently to be described and causing heated water to be fed into the system. Closure of the #1 contacts of the contact group 152 also establishes a parallel circuit from the line 11, through lead 13, #1 contacts, leads 15, 27, 29, heater 40, and leads 31, 33 back to the line 25. The circuit just described is employed only in the event that the boiler is electrically powered as, for example, provided with a burner construction, the operation of which is initiated by electrical means.

Upon closure of the #2 contacts of the contact group 152 due to a flexing of the bi-metallic strip 150, a circuit will extend from the line 11, through lead 13, #2 contacts, lead 35, B' section of the solenoid winding 140, and leads 36, 23, back to the line 25. Energization of B' section of the winding 140 will cause operation of the valve V so as to establish communication between the pipes 18 and 58, thus establishing an hydraulic circuit through the cooler 60 in a manner that will be described subsequently. Upon closure of the #2 contacts, a parallel circuit will also extend from the line 11, through lead 13, #2 contacts of the contact group 152, lead 37, cooler 60 and leads 39, 33, back to the line 25. The cooler 60 may be comprised of the functional elements of a complete air conditioning unit including the usual pump, condenser, and evaporator instrumentalities operatively connected together in series in a closed refrigerant circuit.

A manually operable disabling switch 41 is interposed in a control valve circuit, for example, in the lead 23, and may be opened when it is desired to operate the valve V manually as, for example, when continuous boiler or cooler operation is required.

An overriding control switch 43 may be provided for independent operation of the boiler 40. This switch may be connected between the line 11 and the lead 29 so that upon closure of this switch 43, a circuit will extend from the line 11, through the switch 43, lead 29, boiler 40 and leads 31, 33, back to the line 25. A similar overriding control switch 45 may be provided for independent operation of the cooler 60 and may extend between the line 11 and the lead 37. Upon closure of this latter switch, a circuit will extend from the line 11 through the switch 45, lead 37, cooler 60 and leads 39, 33, back to the line 25.

An independent circuit may be provided for the pump 56, such circuit extending from the line 11, through lead 47, switch 49, lead 51, pump 56 and lead 53 back to the line 25.

Disabling means may be provided for both the boiler 40 and the cooler 60. These means may assume the form of disabling switches 55 and 57 disposed in the leads 27 and 37, respectively. During automatic operation of the apparatus, both of these switches will remain closed.

The circuit diagram of FIG. 7

The electrical circuitry, which is operable under the control of the individual tenant for operating his air conditioning unit 96, is shown in FIG. 7 and includes an electrical circuit for the electric motor 116 which drives the compressor 100. This circuit extends from one side of a source S of current, preferably the house current, through a lead 71, a pair of contacts 73 in associated relation with the thermostat 122, a lead 75, motor 116, and a lead 77 back to the current source. A starting switch SW is interposed in the leads 71 and 77. The contacts 73 are operable under the control of a bi-metallic strip 79 and, when the temperature of water in the branch conduit 118 is above a relatively high temperature, for example, 140° F.,

5

the contacts 73 become open so that the motor 116 may not be operated despite closure of the starting switch SW. By reason of the thermostatic contacts 73, useless heat exchange relationships in the condenser 102 involving small temperature differentials are avoided.

Operation of the system

The system of the present invention is susceptible to flexibility of operation and such operation will be varied according to seasonal temperature changes. However, purely for purposes of discussion herein, it may be assumed that the management of the apartment house will be prepared to operate the controls which are available to it and furnish water within a temperature range of from 140° to 160° F. during a cold period and to furnish relatively cold water within a temperature range of from 85° to 90° F. during the hot period. When operating on this basis and the decision is made to furnish water in the higher temperature range, the switch 41 is opened and the switch 43 is closed. The valve V is then manually set to the position wherein it is shown in FIG. 4 so that the passage 134 in the valve body 132 establishes communication between the lead-out pipe 46 of the boiler 40 and the feed pipe 18. The boiler will be set into operation and water will flow in a closed hydraulic circuit extending from the outlet side 54 of the pump 56, through pipe 52, four-way fitting 50, lead-in pipe 44, boiler 40, lead-out pipe 46, valve V, feed pipe 18, reduction orifice device R and return pipe 20 to the inlet side 64 of the pump 56. Hot water within a range of from 140° to 160° F. will thus be made available at the various floor levels for selective use by the tenants occupying the apartment enclosures 26, 28, 32, 34, and such tenants may, simply by opening their respective valves 72, cause hot water to flow from the feed pipe 18, through branch conduits 92, heaters 90, and branch conduits 94 back to the return pipe 20.

During extreme hot weather when there is little or no likelihood that a tenant will have a demand for heating, the boiler 40 may be disabled by opening the disabling switch 55 and allowing the switch 57 to remain closed so that the cooler may be operated to the exclusion of the boiler. Then, upon closure of the switch 45, the overriding cooler circuit previously described will maintain the cooler in operation continuously. It is to be noted that the cooler 60 is provided, not for the purpose of supplying cooling water to the various apartment enclosures for direct use in the air cooling devices 104, but merely for cooling the refrigerant tubes of the condensers 102. Therefore, the cooler 60 need not have a high cooling rating since water supplied in a temperature range of from 85° to 90° F. is capable of effecting such heat extraction in the condensers as to maintain the various air conditioning units under the control of the individual tenants in efficient operation. Actually, the system will function efficiently in the absence of any overriding control for the cooler 60 inasmuch as the thermostat 66 will, during extremely hot weather, maintain its #1 contacts continuously closed.

During mild weather, such as may occur in inbetween periods when the weather is not sufficiently cold as to justify continuous operation of the boiler 40 or continuous operation of the cooler 60, the demands of the various tenants of the building may differ widely. For example, the tenants who occupy easterly exposed apartment enclosures, such as the enclosures 28, 34 in FIG. 1, may have a demand for cooling during the morning hours when their side of the building becomes heated by the sun. Similarly, the tenants who occupy westerly exposed apartment enclosures, such as the enclosures 26, 32, may have a demand for heating during such morning hours. Conversely, during the afternoon hours when the sun is heating the west side of the building, the demands of these tenants may be the opposite. It is during such days as these that the management will set the system into auto-

75

matic operation by closing the switches 41, 55 and 57, and opening switches 43 and 45. If the temperatures of water in the system is within the range of from 85° to 90° F., the bi-metallic strip 150 of the thermostat 66 will maintain both the #1 and the #2 contacts of the thermostat open so that the valve V will assume the condition wherein it is shown in FIG. 3 with the pipes 18 and 48 in communication and the closed hydraulic circuit extending from the outlet side 54 of the pump 56, through pipe 52, four-way fitting 50, pipe 48, valve V, feed pipe 18, reduction orifice 19, and return pipe 20 to the inlet side 64 of the pump. Water within the predetermined 85° to 90° F. range is thus available in the feed pipe 18 to any tenant who chooses to avail himself of it for condenser cooling purposes and all he needs to do to obtain such water is to open the valve V3 and close the starting switch SW associated with the air conditioning instrumentalities under his control.

The relatively cool water conducted to the condenser 102 through the lead-in branch conduit 118 assimilates much heat and is discharged through the lead-out conduit 120 to the return pipe 20 at an elevated temperature. Thus, any tenants in the easterly exposed apartment enclosures 28, 34 etc. who, at any given time, resort to cooling facilities, will automatically cause a rise in temperature of the water in the return pipe 20. If this rise in temperature carries the water above the predetermined 85° to 90° F. range, the thermostat 66 will function to close the #2 contacts thereof and set the cooler 60 into operation in the manner previously described in connection with the circuit diagram of FIG. 6. The closed hydraulic circuit involving the cooler will extend from the outlet side 54 of the pump 56, through pipe 52, four-way fitting 50, pipe 62, cooler 60, pipe 58, valve V, feed pipe 18, reduction device 19 and return pipe 20 to the inlet side 64 of the pump 56.

The heated water discharged by the tenants in the apartment enclosures having easterly exposures will not necessarily raise the temperature of water in the return pipe 20 above the predetermined range of from 85° to 90° F., inasmuch as water in this temperature range is adequate for heat exchange purposes when used in the heaters 90 of the various apartment enclosures having westerly exposures. The tenants occupying apartment enclosures having westerly exposures, being shielded from the sun, may have a demand for heating and, in such case, it is necessary merely for the individual tenant to open the valve V2 and admit water to the heater 90. Such tenants as have a demand for heating will thus tend to balance, so to speak, the tenants who have a demand for cooling inasmuch as, by their use of hot water in the heaters 90, the temperature of the water is reduced and returned to the pump 56 through the return pipe 20. Therein lies one of the principal features of the present invention.

It is obvious that, during the afternoon hours, the demands of the various tenants will be reversed but a condition of balance will still obtain when the number of tenants resorting to cooling facilities is substantially equal to the number of tenants resorting to heating facilities.

If the number of tenants resorting to heating facilities materially exceeds the number of tenants resorting to cooling facilities so that, by their discharged and cooled water, the temperature of water in the closed hydraulic system falls below the predetermined 85° to 90° F. range, the #1 contacts of the thermostat 66 will become closed and the boiler 40 will be set into operation in the manner previously described in connection with the circuit diagram of FIG. 6. The closed hydraulic circuit involving the boiler will extend from the outlet side of the pump 54, through pipe 52, four-way fitting 50, pipe 44, boiler 40, lead-out pipe 46, valve V, feed pipe 18, pressure reduction device 19, and return pipe 20 to the inlet side 64 of the pump 56.

Whether the boiler or the cooler be set into operation by the action of the thermostat 66 and the electrical

instrumentalities associated therewith, in either event, the temperature of the water within the closed hydraulic system will be promptly restored to the predetermined range of from 85° to 90° F. This temperature range is adequate on the one hand for heating purposes insofar as such tenants as may have a demand for heating facilities are concerned. It is adequate on the other hand for cooling purposes insofar as such tenants as may have a demand for cooling facilities are concerned. Stated otherwise and briefly, the system will automatically remain in thermal balance if the tenant demand at any given time for heating and cooling, respectively, is equal. If one demand exceeds the other to an appreciable degree, either the heater 40 or the cooler 60 will operate to restore the thermal balance.

The invention is not to be limited to the exact arrangement of parts shown in the accompanying drawings or described in this specification as various changes in the details of construction may be resorted to without departing from the spirit of the invention. For example, while the electrical circuitry shown herein in FIG. 6 embodies direct acting thermostatic control of the valve V, boiler 40 and cooler 60, utilizing a thermostat of the movable contact type, other circuitry is contemplated. In some instances, it may be deemed advisable to employ relay-actuated circuit devices, including or not as desired, thermionic vacuum tube or other amplifier devices. Duplication or multiplication of heating and cooling instrumentalities or other parts of the system is also contemplated within the scope of the invention. Therefore, only insofar as the invention has particularly been pointed out in the accompanying claim is the same to be limited.

Having thus described the invention, what I claim as new and desire to secure by Letters Patent is:

In an air conditioning system of the character described, in combination, a multi-story building having a basement, superimposed floors, a ceiling above each floor defining, in combination with the floor immediately therebeneath, an inhabitable enclosure, a structural shaft extending upwardly through the building from the basement ceiling through the floors, there being a lateral opening in said shaft at each enclosure-level establishing communication between the shaft and the enclosure at said level, a water riser pipe and a water return pipe extending upwardly in said shaft from the basement to a region adjacent the uppermost enclosure-level, a heat exchange device in each enclosure, branch pipes extending through said lateral openings and connecting the heat exchange devices with the water riser and water return pipes, a shut-off valve for each heat exchange device and disposed in one of the branch pipes leading thereto, an air conditioning unit disposed in each enclosure and including a compressor, a condenser and an evaporator operatively connected together in a refrigerant circuit, an electric circuit for the motor, the condenser being of the water-cooled type, branch pipes extending through the lateral openings and connecting the condensers of the air conditioning units with the water riser and water return pipes for condenser-cooling purposes, a shut-off valve for each condenser and disposed in one of the branch pipes leading thereto, a thermostat responsive to the temperature of water in said riser pipe and individual to each electric circuit for disabling the same when the temperature of water is above a predetermined degree, said water riser and return pipes being operatively connected in a closed hydraulic circuit, a water circulating pump disposed in said hydraulic circuit and positioned in the basement, a water heater in said basement, a water cooler in said basement, a solenoid-actuated control valve operable selectively to connect the heater and the cooler in the hydraulic circuit, each to the exclusion of the other, and to exclude both the heater and the cooler from the hydraulic circuit, a thermostat responsive to the temperature of water in said return pipe, said latter thermo-

stat being operable when the temperature of water in the return pipe falls below a predetermined degree to actuate the control valve to connect the heater in the hydraulic circuit and being operable when the temperature of water in the return pipe rises above a predetermined degree to actuate the control valve to connect the cooler in the hydraulic circuit, said heat exchange unit and evaporator being of the finned tubing type and being physically disposed in tandem, and an electrically operable fan in each enclosure common to the evaporator and heat exchange unit for drawing air successively through the same.
